UNITED STATES PATENT OFFICE

126,829

DESIGN FOR A GARMENT HANGER

Minny M. Avery, Glendale, Calif.

Application October 15, 1938, Serial No. 80,480

Term of patent 3½ years

To all whom it may concern:

Be it known that I, Minny M. Avery, a citizen of the United States, residing at Glendale, county of Los Angeles, State of California, have invented a new, original, and ornamental Design for a Garment Hanger, of which the following is a specification, reference being had to the accompanying drawing, forming a part thereof.

I claim:

The ornamental design for a garment hanger, as shown.

MINNY M. AVERY.
